US00D687536S

(12) **United States Design Patent**
Guarraia et al.

(10) **Patent No.:** **US D687,536 S**
(45) **Date of Patent:** **** Aug. 6, 2013**

(54) **INFUSION DEVICE**

(75) Inventors: **Mark Joseph Guarraia**, Cranston, RI (US); **Margaux Frances Boyaval**, Warwick, RI (US); **Ryan James Shafer**, Whitinsville, MA (US)

(73) Assignee: **Becton, Dickinson and Company**, Franklin Lakes, NJ (US)

(**) Term: **14 Years**

(21) Appl. No.: **29/418,277**

(22) Filed: **Apr. 13, 2012**

(51) **LOC (9) Cl. 24-01**

(52) **U.S. Cl.**

USPC **D24/108; D24/111**

(58) **Field of Classification Search**

USPC D24/108, 107, 118, 121, 129, 162, D24/164, 167, 169, 114, 111; 604/6.09, 180, 604/151, 154, 164.08, 93.01, 153, 141, 54, 604/533, 506, 19, 48, 500; D15/7, 8

(57) **CLAIM**

The ornamental design for an infusion device, as shown and described.

DESCRIPTION

FIG. 1 is a perspective view of an infusion device showing our new design;

FIG. 2 is a top view of the infusion device shown in FIG. 1; FIG. 3 is a left side elevational view of the infusion device shown in FIG. 1;

FIG. 4 is a front elevational view of the infusion device shown in FIG. 1;

FIG. 5 is a rear elevational view of the infusion device shown in FIG. 1;

FIG. 6 is a right side elevational view of the infusion device shown in FIG. 1; and,

FIG. 7 is a bottom view of the infusion device shown in FIG. 1.

The broken line showing of two rounded features in FIG. 7 is for the purpose of illustrating portions of the article and forms no part of the claim.

1 Claim, 4 Drawing Sheets
